UNITED STATES PATENT OFFICE.

CHARLES STEFFEL, OF GRANITE CITY, ILLINOIS; FRANK B. SANDERS ADMINISTRATOR OF SAID CHARLES STEFFEL, DECEASED.

OIL BURNER.

1,403,986.

Specification of Letters Patent. Patented Jan. 17, 1922.

Application filed June 24, 1920. Serial No. 391,452.

To all whom it may concern:

Be it known that I, CHARLES STEFFEL, a citizen of the United States, residing at Granite City, Illinois, have invented a certain new and useful Improvement in Oil Burners, of which the following is a full, clear, and exact description, such as will enable others skilled in the art to which it appertains to make and use the same.

10 This invention relates to oil burners, and has for its main object to provide an oil burner of novel construction that will split up or divide into small particles the large globules of oil, and thus effect a great saving in the quantity of oil used, due to the fact that all of the oil supplied to the burner will be burned or utilized.

15 Other objects and desirable features of my invention will be hereinafter pointed out.

Figure 1 is a side elevational view of an oil burner constructed in accordance with my invention.

20 Figure 2 is a longitudinal sectional view of said burner.

Figure 3 is a front end elevational view of the burner.

25 Figure 4 is a rear end elevational view of the burner with the oil and steam pipes removed; and

Figure 5 is a cross sectional view of the burner, taken on the line 5—5 of Figure 2, looking in the direction indicated by the arrows.

30 Referring to the drawings which illustrate the preferred form of my invention, A designates a member provided with a mixing chamber B to which oil and an atomizing medium such as steam or compressed air are supplied through a pipe 1 and a pipe 1^a that is arranged inside of the pipe 1. Preferably, oil is supplied through the pipe 1 and steam or compressed air through the pipe 1^a. The mixing chamber

40 B is preferably formed by two transversely-disposed bores or spaces 2 in the member B arranged in parallel relation, as shown in Figures 2 and 5 and connected with each other by a narrow or contracted passageway 3. Said mixing chamber is provided

45 with a discharge opening, preferably in the form of a narrow, elongated slot 4, that leads from the upper end of said mixing chamber and terminates in the front end

50 of the member A, and said mixing chamber

is also provided with inlet openings through which oil and an atomizing medium are admitted to said chamber. In the preferred form of my invention, as herein shown, oil is supplied to the mixing chamber through 60 an opening 5 arranged at the lower end of said chamber, and steam or compressed air is supplied to said chamber through an opening 6 located preferably at a point just below the passageway 3 that connects the 65 two spaces or portions 2 of the mixing chamber with each other.

In order that the large globules of oil which enter the mixing chamber B will be split up or divided into small particles, I 70 have provided said mixing chamber with numerous sharp projections or corners 7 against which the globules of oil strike in passing through the mixing chamber. I prefer to equip said mixing chamber with 75 a projection 7 formed by the upper edge of the oil inlet opening 5, a plurality of projections 7 arranged at opposite sides of the contracted passageway 3 between the two portions 2 of the mixing chamber and a 80 projection 7 formed by the lower edge of the discharge opening 4 which leads from the upper end of the mixing chamber. When the burner is in use the oil that is supplied to the mixing chamber B through 85 the inlet opening 5 will be atomized by the steam or compressed air that is supplied to the mixing chamber through the opening 6, and as the mixing chamber is provided with

numerous sharp corners or projections 7 90 which the globules of oil encounter in passing through the mixing chamber, the large globules of oil will be broken up sufficiently to insure all of the oil being burned, thereby effecting a great saving in the quantity 95 of fuel used, due to the fact that all of the fuel is burned. In fact, a burner of the construction above described will atomize and burn very heavy oil like tar oil, pitch tar and other heavy fluids and liquids which 100 cannot be burned successfully in the oil burners now in general commercial use.

Means is also provided for causing the oil to swirl or flow in a spiral path just before it enters the mixing chamber B. In the embodiment of my invention herein illustrated said means is formed by spiral grooves or ribs 8 on a plug C arranged inside of the pipe 1 and provided with a passageway 9 through which steam or compressed air is 110

supplied to the inlet opening 6 of the mixing chamber, said plug C being preferably mounted on the steam or compressed air supply pipe 1^a and provided at its front end 5 with a nozzle 10 that fits in a bore in the member A, as shown in Figure 2. The rear end of the nozzle 10 is flared and is so proportioned that the front end of the spirally grooved or fluted portion of the plug C will 10 be held spaced away from the member A far enough to permit the oil to pass downwardly to the oil inlet 5 at the lower side of the mixing chamber. If desired, the oil inlet 5 can be provided at its receiving end 15 with a mouth 5^a having an upwardly-inclined bottom wall, as shown in Figures 2 and 4, so as to direct the oil into the inlet opening 5.

My improved burner is intended to be 20 used in the same manner as the oil burners now in general use. When used in an open hearth furnace the pipe 1 is made long enough to project into the furnace a considerable distance, and said pipe 1 and the 25 steam or compressed air supply pipe 1^a that is arranged inside of same are connected by ordinary T pipe fittings to the oil and steam supply pipes, thus overcoming the necessity of using special castings for connecting the 30 pipes of the burner with the supply pipes, as is necessary with the oil burners now generally used in open hearth furnaces. Furthermore, as the steam or air used to atomize the oil is supplied to the mixing chamber 35 through a pipe 1^a which may extend a considerable distance into the furnace, said steam or air will be superheated while it is passing from the supply pipe to the point where it mixes with the oil. While it is not 40 essential that the discharge opening 4 leading from the mixing chamber to be in the form of a narrow, elongated slot, still I prefer to make the discharge opening in this 45 form when the burner is designed for use with an open hearth furnace, on account of the fact that such a construction produces a wide, flat flame that spreads out over a relatively great area.

Having thus described my invention, what

I claim as new and desire to secure by Letters Patent, is:

1. An oil burner, comprising a member mounted on the end of an oil pipe and provided with a mixing chamber composed of two separate and distinct portions connected 55 with each other by a contracted passageway, said member having a discharge opening in the front end of same that communicates with one portion of the mixing chamber, an inlet leading from the other portion of said mixing chamber to the interior of the oil pipe on which said member is mounted, a device arranged inside of the oil pipe and combined with said member in such a way that it introduces an atomizing medium into 60 said mixing chamber intermediate the two portions of said chamber, sharp pointed corners or projections in the passageway in said member through which the oil travels for effectively breaking up the large globules 65 of oil, and spiral grooves or ribs on the exterior of said device for imparting a swirling action to the oil that is supplied through the pipe on which said member is mounted.

2. An oil burner, comprising a member 70 that is mounted on the end of an oil pipe and provided with a mixing chamber formed by two transversely-disposed bores in said member arranged one above the other and connected together by a contracted passageway, a discharge opening in the front end 75 wall of said member consisting of a narrow slot that leads from the upper bore of said mixing chamber, an inlet leading from the lower bore of said mixing chamber to the interior of said oil pipe on which said member is mounted, a device in the oil pipe 80 mounted on the end of a pipe through which an atomizing medium is supplied and provided at its front end with a nozzle that fits in an opening in said member, said nozzle having a passageway therein through 85 which the atomizing medium is admitted to the mixing chamber, and spiral grooves or ribs on the exterior of said device for imparting a swirling action to the oil that is 90 supplied to the burner.

CHARLES STEFFEL.
